CARRIER WHEEL DEVICE

Application filed July 12, 1928, Serial No. 292,269. Renewed June 27, 1930.

This invention relates to a carrier wheel device and more particularly to means for securing the carrier wheels to the shafts of open annealing furnaces.

5 In annealing sheets, the sheets are passed through the furnace over a succession of revolving wheels mounted on water cooled horizontal shafts. The wheels overlap so that upon rotation of the wheels the sheets are 10 passed from wheel to wheel through the furnace. The shaft and wheels mounted thereon are suggestive of a disk harrow with the exception, of course, that the rims of the 15 wheels are wide enough to support the sheets 20 passing through the furnace without marking the sheets. Much trouble has been experienced in connecting the wheels which support the sheets to the shafts because of the high temperature which it is necessary to

employ in these furnaces. It previously has been proposed to connect the wheels to the shafts, which ordinarily are hollow in order to allow air or other cooling fluid to be passed therethrough, by means of 25 studs screwed into the shafts and co-operating with recesses provided in the hubs of the wheels.

This practice is objectionable, however, for the reason that in use the expansion of the 30 various parts causes the studs to become displaced from their recesses thereby allowing the wheels to rotate upon the shafts.

It also has been proposed to connect the wheels and shaft by making the wheels in 35 sections and bolting the wheels together. Slots were formed in the shafts in order to receive the bolts so that the bolts not only connected the parts of the wheel together but also prevented longitudinal movement of 40 the wheels along the shafts. When this arrangement was employed the rims of the wheels were welded so as to provide a continuous rim. It was found that in time the cast-iron sleeves or spacers which were used 45 to space the wheels on the shafts expanded because of the heat, the bolts lost their tension which resulted in the spacers falling off of the shaft into the furnace and allowed the wheels to slide along the shafts. This caused 50 large openings in the furnace which allowed

the sheets to drop down and seriously affected furnace operation.

We have discovered a means for connecting the carrier wheels of an annealing furnace to the shafts by which the above-mentioned disadvantages are obviated. Although our invention is particularly applicable to annealing furnaces, it may also be applied in any place where a device is needed for driving disks or wheels in any type of furnace where 55 a caterpillar action in floor movement is employed in making transit through the heating medium.

In the drawings which show the present preferred embodiment of the invention— 60

Figure 1 is a transverse section through an annealing furnace and carrier wheel shaft, parts being shown in elevation; and

Figure 2 is a sectional view taken on the line II—II of Figure 1. 70

Referring to the preferred embodiment of the invention shown in the drawings, there is provided an annealing furnace 2 through which the sheets are passed in the annealing process. The furnace is provided with a plurality of shafts arranged transversely of the furnace, on each of which a plurality of carrier wheels adapted to transport the sheets through the furnace, are mounted. As shown in the drawings, openings 3 are provided in 80 the sides of the annealing furnace and are adapted to receive the shafts 4 on which the carrier wheels 5 are mounted. The shafts 4 are supported in bearings 6 arranged outside of the furnace and the shafts are adapted to 85 be rotated from any desired source through the gear 7 arranged on the end of the shaft.

In order to overcome or minimize the effects of the unequal expansion of the rims and hubs of the carrier wheels, the wheels 90 preferably are provided with curved spokes 8. The rims 9 of the wheels are of a sufficient width so that they do not mar the sheets which are supported by the rims of the wheels. The wheels are provided with non-circular hubs 10 which in the preferred embodiment are shown as substantially square. 95

Our invention particularly contemplates means for connecting wheels provided with non-circular hubs, with a circular shaft and, 100

as shown, we accomplish this result by employing segmental liners between the shafts and the hubs.

In the form shown in the drawings we 5 employ quadrantal segmental liners 11 which cooperate with the square hubs, but it will be apparent that the hubs may be made of other angular shapes and the segmental liners may be shaped accordingly, if desired. The 10 segments are arranged between the hubs of the carrier wheels and the shafts so as to cause rotation of the wheels as the shafts are rotated.

In assembling the device shown in Figure 15 1, the sleeve 12 is arranged on the shaft 4 and the sleeve is prevented from rotating with relation to the shaft by tightening set screw 13. The sleeve 12 is provided at its right hand end with a series of notches 12' 20 which co-operate with projections 14' on the sleeve 14 to cause the sleeves to rotate together. The right hand end of the sleeve 14 is reduced in size as shown at 15 in order that it may fit within the square hub of the left 25 hand carrier wheel 5. A carrier wheel is then slid onto the reduced portion 15 of the sleeve 14. Segmental liners 11 are then inserted into the right hand side of the hub and thereafter other carrier wheels are slid 30 over the segmental liners. The right hand end of the shaft is similarly provided with sleeves 16 and 17. It will be obvious that a single sleeve may be substituted for the two sleeves 12 and 14 or for the two sleeves 16 35 and 17 if desired, and that the wheels, liners, and shaft may be assembled before fitting the sleeves 12, 14, 16 and 17 to the shaft.

In the embodiment shown in the drawings 40 the carrier wheels are maintained in spaced position by the hubs of the wheels. If it is desired to space the wheels farther apart, spacing sleeves may be employed between the hubs.

When power is applied to the gear 7 it 45 rotates the shaft 4. The sleeves 12 and 14 are rotated and cause the left hand carrier wheel 5 to rotate with the shaft. Each of the other carrier wheels is caused to rotate due to the arrangement of the segmental liners 11 50 between the shaft and the hubs of the wheels.

From the above description it will be seen 55 that we have in effect transformed a circular shaft into a square shaft, and have in effect provided a unitary connection between the carrier wheels, segmental liners, sleeves and shaft.

Although the various parts may be made 60 of any desired materials we have found it particularly advantageous to employ nickel chrome wheel hubs.

It is to be understood that the form of the invention herewith shown and described is to be taken as a preferred example of the same and that the invention may be otherwise 65 embodied without departing from the spirit

of the invention or the scope of the following claims.

We claim:

1. A device of the character described comprising a circular shaft, a plurality of wheels provided with non-circular hubs, and a segmental liner for said shaft adapted to connect said wheels with said shaft. 70

2. A device of the character described comprising a circular shaft, a plurality of wheels provided with substantially square hubs, and a plurality of substantially quadrantal segmental liners adapted to connect said wheels with said shaft. 75

3. A device of the character described comprising a circular shaft, a plurality of wheels provided with curved spokes and substantially square hubs, a plurality of substantially quadrantal segmental liners adapted to connect said wheels with said shaft, 80 and sleeves on said shaft adapted to co-operate with the end wheels on said shaft to transmit power from said shaft to said wheels. 85

4. A device of the character described comprising a circular shaft, a plurality of carrier wheels provided with non-circular hubs of larger dimensions than said shaft, and a plurality of segmental liners arranged between said shaft and the hubs and adapted 90 to cause said shaft and said wheels to rotate together. 95

5. A device of the character described comprising a circular shaft, a plurality of wheels associated therewith at least one of the wheels being operatively connected to the shaft, the hubs of the wheels having non-circular openings therein larger than the diameter 100 of the shaft, and a liner on the outside of the shaft connecting the wheels to each other to cause them to rotate together when the shaft is rotated. 105

6. A device of the character described comprising a circular shaft, a plurality of wheels associated therewith at least one of the wheels being operatively connected to the shaft, the hubs of the wheels having square openings therein larger than the diameter of the shaft, and a liner on the outside of the shaft connecting the wheels to each other to cause them to rotate together when the shaft is rotated. 115

In testimony whereof we have hereunto set our hands.

ARTHUR S. SHOFFSTALL.
HERMAN M. BROWN.
